FIGURE 1 is a front view of a holder for measuring implements or the like, showing my new design;

FIGURE 2 is a section taken on the line 2—2 of FIGURE 1;

FIGURE 3 is a section taken on the line 3—3 of FIGURE 1;

FIGURE 4 is a section taken on the line 4—4 of FIGURE 1;

FIGURE 5 is a section drawn in perspective, taken on the line 5—5 of FIGURE 1; and

FIGURE 6 is a section taken on the line 6—6 of FIGURE 1.

The essential features of my design for a holder are shown in full lines, the broken line showing of a measur-

ing cup and measuring spoon in FIG. 1 being for illustrative purposes only.

I claim:

The ornamental design for a holder for measuring implements or the like, as shown and described.
